UNITED STATES PATENT OFFICE.

CHARLES FRANCIS JENKINS, OF WASHINGTON, DISTRICT OF COLUMBIA, ASSIGNOR TO
THE GRAPHOSCOPE COMPANY, OF WASHINGTON, DISTRICT OF COLUMBIA, A CORPO-
RATION OF DELAWARE.

PICTURE-PROJECTING APPARATUS.

1,327,280.

Specification of Letters Patent. Patented Jan. 6, 1920.

Application filed October 17, 1916. Serial No. 126,063.

To all whom it may concern:

Be it known that I, CHARLES FRANCIS JENKINS, a citizen of the United States, and resident of Washington, in the District of Columbia, have invented certain new and useful Improvements in Picture-Projecting Apparatus, of which the following is a specification, reference being had therein to the accompanying drawing.

This invention relates to apparatus especially intended for projecting pictures by means of an arc light. The principal objects are to provide, in a casing which can be adjusted bodily parallel to the beam of light, an arc light which can be adjusted bodily, within the casing, in distance from the condensing lens, and having means whereby one or more of the carbons can be adjusted with certainty by a single movement, according to the way the parts are seized by the hand.

In the accompanying drawings,

Figure 1 is a view showing the apparatus partly in axial vertical section.

Fig. 2 is a plan view of the same devices.

Fig. 3 is a section on the line 3—3, Fig. 2.

Fig. 4 is a section on the line 4—4, of Fig. 2.

In these views, 1 represents a table upon which is a standard 2 mounted for longitudinal adjustment in a slot 3. This standard passes upward through a slot 5 in the bottom of a casing 6 in the walls of which are fixed parallel rods 7 in a horizontal plane. Within the casing the standard supports a rigid spider 8, Figs. 1 and 2, having four arms, two of which support each of the rods by means of bearings in their upturned ends and thus carry the casing. Upon the rods is mounted a saddle 9 carrying a heavy vertical insulating plate 10 transverse to the rods. A screw 11, rotating without advance in the casing, engages the saddle and adjusts it along the rods 7. Three carbons 12, 13, 14 are shown, the first passing through an opening in the plate 10 in the axial line of the beam of projecting light and resting in a V-shaped trough 15 supported by a bell-crank 16 adjustably secured to the plate 10 and connected to one electric terminal 17. The carbon 12 is held in the trough by the sharp corners of disks 18 of emery, other forms of corundum, or analogous material having similarly hard and

sharp particles capable of effectively engaging light carbons fixed on a rotary shaft 19 mounted in bearings 21 upon a bar pivoted at the center of its circular end portion 20, to the plate 10 and drawn toward the trough by a spring 22. The bell crank 16 is pivoted to the plate 10 near its angle and its end above the terminal 17 is provided with a stud which passes through the plate 10 in a suitable slot and is clamped in any desired position by a nut 16', Fig. 2. By loosening this nut the bell crank is permitted to swing and press either a large or a small carbon against the disks 18, and the bell crank may then be locked by the nut 16'. By this expedient only slight adjustment of the disks 18 is ever necessary. The carbons 13, 14 in the horizontal plane of the carbon 12 diverge oppositely from the axial line thereof, and are pressed against similar emery disks 23, 24 mounted upon short vertical shafts 25, 26, by pivotally mounted troughs 27, 28 and springs 29, 30, current being brought to the troughs by conductors 40, 41 entering the casing at 42. These devices like those for the carbon 12 are supported from the plate 10 upon rigid studs 10', Figs. 1 and 2. The emery disks 23 are rotated by a shaft 31, having a milled head 32 and acting through bevel gears 33. The disks 24 are similarly rotated by a hollow shaft 34 concentric with 31 and acting through bevel gears 35, this hollow shaft having a milled operating head 36 alongside the head 32 but slightly separated therefrom, and the disks 18 are rotated by a second hollow shaft or sleeve 37 inclosing the hollow shaft 34 and acting through sprocket wheels 38, 39 connected by a chain belt 43, this sleeve being rotated by a milled head 44 alongside the heads 32 and 36. The three concentric shafts pass out through a slot at 6', Fig. 2, in the casing and their external milled heads are at such distance apart that any one or more may be engaged by the fingers and rotated, one, two or all the shafts being rotated by a single movement of the fingers.

The lens holder 45 contains no novelty herein claimed.

What I claim is:

1. For holding a carbon and adjusting it longitudinally, a trough member for resting against one side of the carbon, a second

105

member comprising two disks of corundum separated to a distance less than the carbon's diameter, and resting against the opposite side of the carbon, a spring urging one of 5 the members toward its companion, and means for manually rotating the disks.

2. The combination with a carbon of two other carbons in the plane of the first, diverging from its end and forming arc 10 gaps therewith, of means whereby the hand of the operator by a single movement may axially adjust one, two, or all the carbons, as desired.

3. The combination with a carbon of two other carbons in the plane of the first, 15 diverging from its end and forming arc gaps therewith, of means whereby the hand of the operator by a single movement may axially adjust one, two, or all the carbons, as desired, and means for at will moving 20 all the carbons along the axial line of one of them.

In testimony whereof I hereunto affix my signature.

CHARLES FRANCIS JENKINS.
